H. A. CLARK

SHEAVE TENSIONING AND ADJUSTING DEVICE

Filed June 14, 1926

Patented Feb. 15, 1927.

1,617,668

UNITED STATES PATENT OFFICE.

HARRY A. CLARK, OF WICHITA FALLS, TEXAS.

SHEAVE TENSIONING AND ADJUSTING DEVICE.

Application filed June 14, 1926. Serial No. 115,856.

This invention relates to portable drilling, spudding and clean-out machines especially designed for oil field operations, and the invention particularly resides in an attachment 5 for such machines to be applied to the sheave of the spudding arms, and by which is reduced to a minimum the shock imposed upon this element when the spudding line is operated.

10 The invention further aims among its objects in so altering the position of the spudding sheave, to eliminate frequent breakage of the sheave hanger, and consequently the repair expenses and time consumed in making such repairs.

15 With the foregoing and other objects and advantages in view, the invention has particular reference to its novel feature of construction and arrangement of parts, by which 20 the said objects are attained, and which will be manifested in the course of the following detail description and made a subject of the annexed drawings, wherein:

25 Figure 1 is a fragmentary view of the usual portable type of drilling machines with portions cut away to illustrate the position of the invention thereon.

Figure 2 is a side elevational view of the invention, and

30 Figure 3 is a top plan view thereof. Although tensioning or cushioning means is provided for the present spudding line sheave, the position of the hanger upon which this means is mounted, must necessarily be in such position that when breakage occurs, it will be forcibly thrown by the releasing action of the spring tensioning means directly toward the point of operations, and frequently falls within the hole 35 being drilled or cleaned. Should this be the case, considerable time and effort is spent fishing for the broken part to remove the same.

The present invention proposes to obviate 40 the foregoing disadvantage by altering the position of the tensioning means in such a manner that should breakage occur the fractured member would be directed away from the hole.

45 With the above in view, attention is directed to Figure 1 which shows a fragmentary side view of a portable drilling machine having the usual spudding arms 1, which impart reciprocating motion to the drilling or spudding cable 2, in a manner such as will presently be disclosed.

Rotary motion is imparted to the pitman arms 3 by its connection to the crank arm 4, which latter of course is driven by a suitable engine mounted upon the frame of the machine. The line 2, is first wound about the large drilling drum 5, from which point it extends, over a sheave at the rear end of the machine, (not shown) thence under the sheave 6, forming part of the invention, 60 whereupon it continues to the top of the mast 7, and when the latter is in extended operative position the line is used to actuate tools in the hole. Strain upon the sheave 6 is excessive, and as stated previously frequent breakage of this member is consequently the result.

Now, the invention consists of the structure especially illustrated in Figures 2 and 3, composed of a lateral shaft 8, rotating in 75 bearings 9 affixed to opposing beams 1. A double bell crank 10, having its central bearing mounted upon the shaft 8 is provided, and intermediate the sides of the crank 10 the sheave 6 is rotatably mounted, while to 80 its lower bearing a rod 11 is secured, and extends rearwardly through a reinforced lateral beam 12, and is freely movable therein. A plate 13 is then applied to the protruding end of the rod and acts as a seat for a compression spring 14. A similar plate 15 is applied over the rod to engage the opposite end of the spring, after which suitable lock nuts 16 are threaded upon the end of the rod to prevent displacement of the spring. 90 It will be observed that the depending arm of the bell crank 10 is provided with a series of apertures 17 in which the end of the rod 11 may be selectively engaged to alter the position of the sheave 6 with respect to the 95 beams 1.

From the foregoing description, it is apparent that excessive strain upon the sheave 6 resulting from irregular and forcible pulls from either end of the line will be alleviated by the arrangement shown, as pivotal movement of the bell crank 10 to raise the sheave 6 in accordance with the pull upon the cable will move the rod 11 to compress the spring 14. Should the strain be so great as to strip the threads on the end of the rod and release the spring 14, the latter is so placed that it is impossible for the same to enter the hole to hinder or interrupt the drilling operation.

100 It should be understood herein that while the invention has been specifically described,

the same should not be restricted to such limitation and that certain minor changes and modifications may be resorted to as fall within the meaning and scope of the following claims.

I claim:

1. In a well drilling machine, a frame, a pair of spaced spudding arms, a transverse shaft on the arms adjacent the free ends thereof, a bell crank mounted on the shaft and having a sheave on one of its arms which extends above the spudding arms, a perforated transverse beam interposed between the spudding arms and arranged in the plane thereof, the other arm of the bell crank extending downwardly between the spudding arms, a rod arranged in the space between the spudding arms and in substantially the plane thereof and connected at one end to said other bell crank arm and at its opposite end projecting rearwardly through the beam perforation, and a coil spring on the projecting end of the rod abutting the

beam, the said other arm of the bell crank, the rod and the spring being each housed by 25 and between the spudding arms.

2. In a well drilling machine, a frame, a pair of spaced spudding arms, a transverse shaft on the arms, adjacent the free ends thereof, a bell crank on the shaft having a 30 sheave on one of its arms which extends above the spudding arms, the other arm of the bell crank extending downwardly between the spudding arms, a guide between the arms spaced rearwardly of the shaft, a 35 rod arranged in the space between the spudding arms and connected at one end to said other bell crank arm, and having its other end extending through the guide, and spring means connected to the rod to tension the same, the said other arm of the bell crank, the rod and the spring device being each housed by and between the spudding arms. 40

In testimony whereof I affix my signature.

HARRY A. CLARK.
